UNITED STATES PATENT OFFICE.

EUSTACE OXLEY, OF LYNN, MASSACHUSETTS, ASSIGNOR TO THE GENERAL ELECTRIC COMPANY, OF NEW YORK.

MULTIRATE-METER.

SPECIFICATION forming part of Letters Patent No. 657,829, dated September 11, 1900.

Application filed August 7, 1899. Serial No. 728,363. (No model.)

To all whom it may concern:

Be it known that I, EUSTACE OXLEY, a subject of the Queen of Great Britain, residing at Lynn, in the county of Essex, State of Massachusetts, have invented certain new and useful Improvements in Controlling Multirate-Meters, (Case No. 975,) of which the following is a specification.

In prior patents granted to me I have described control systems for multirate-meters by which any one of a plurality of electric meters at a consumer's station may be thrown into operation at a desired time from a controlling-point of the system. Such meters, as is understood by those familiar with the art, are employed for the purpose of affording the consumer an incentive to use current more freely during certain periods of the day or night when the load on the system is light, and in order to provide an easy accounting of his drafts of current a meter having different recording rates or a plurality of meters having such different recording rates may be employed. I have heretofore patented various types of control systems for cutting such multirate-meters into and out of action at the proper time. In some of these a grounded circuit is employed and in others an independent control-wire. My present invention relates more particularly to the former mode of control, the design being to prevent interference with the control system in case of an accidental ground. In preventing interference with the action of the control-circuit by an accidental ground I provide devices by which the circuit is operated under the influence of the ground and is then restored to the *status quo* prior to interruption. I preferably also protect the circuit, so that in case of a permanent ground the circuit will be interrupted. I provide also an instrument located at the consumer's station to prevent fraud upon the supply company by an unscrupulous consumer by bringing within the cognizance of an employee of the company a change of the meter connections.

The several features of novelty in my invention will be more particularly described hereinafter and will be definitely indicated in the claims.

In the drawings, Figure 1 is a diagram of

a system embodying my improvements, and Fig. 2 is a diagram of a modification.

I have shown in the drawings my system as applied to a plurality of independent meters. It will, however, be understood by those who are familiar with the art that in lieu of two or more independent meters being employed a single registering device in the controlling-circuit in which resistance or other devices may be interposed to vary the registering rate may be employed as an equivalent. I have also shown the system as applied to a three-wire distributing system, although the improvements may be applied to systems of any desired number of distributing-wires.

Referring to the drawings, M' M^2 represent a multirate-meter, shown diagrammatically as two independent devices operated by the current to be measured, one to register current consumption at the low rate and the other at the full rate, accordingly as the control-switch located at the central station is set.

1 2 3 represent the distributing-mains of a three-wire system. In the grounded branch of one wire—say the neutral wire 2 at any consumer's station—is placed a rate-determining device 4, comprising two electromagnets 5 5^a, with confronting poles, between which is placed a pivoted armature carrying insulated contacts 6 6^a, the former connected to the neutral wire and the latter grounded at G. Coöperating with these contacts at the extremes of movement of the armature are fixed contacts 7 7^a 8 8^a, the contacts 7 8 connecting, respectively, with one terminal of the armature-circuit or other shunt-circuit of the meter-motor. The type of meter shown in the drawings is the well-known Thomson recording-wattmeter, the construction of which will be sufficiently understood from the drawings by those familiar with the art. The other terminal of the shunt-circuit of the motor may connect with one of the mains, as 3. The field-magnet circuit of the motor is in series relation to the current-consuming devices and may be connected across the outside mains 1 and 3. The wires 2 and 3, as shown in the drawings, are control-wires, and the magnets 5 5^a may be put into communication with these control-wires, respectively, by means of the contacts 7^a and 8^a. At the control-station I

have shown a magnetically-controlled device similar in its mode of operation to that shown at 4, just described, which may be called a "rate-maintainer," inasmuch as its function 5 is to preserve the rate for which the meter was set in case of accidental derangement by a temporary ground. The armature in this contrivance carries a metallic plate 9, playing between two sets of contact clips or stops 10 10^a and 11 11^a. The plate is electrically connected with ground through a fuse-plug 12. The contacts 10 and 11 connect, respectively, with two fixed contacts 13 13^a, with which co-operates a double-arm switch 14, the levers of 15 which connect, respectively, with control-mains 2 and 3. The contact-clips 10^a and 11^a connect, respectively, with the electromagnets of the rate-maintainer and thence with the control-wires 2 and 3. As thus organized, 20 an employee at the central station by operating the switch 14 to the open contact may always change the rate of a meter at a consumer's station, and when such a change is made the rate-maintainer and rate-controller 25 at the two stations shift their armatures and change the controlling-circuits into a position where they may be rendered operative by a subsequent operation of the controlling-switch 14. Obviously such a change, since it 30 is a grounded system, leaves the apparatus open to a change of meter connections in case of an accidental ground on the system by which potential is put upon the controlling-magnets; but by the arrangements of the 35 circuits described such a change will re-establish the apparatus in a position where it will be under control of the switch as last set and an automatic restoring of the switch to that condition will follow. In case the ground is per- 40 manent and endures the fuse will be blown and the attention of the employee assured.

In case of a fraudulent interference with the adjustment of the circuits on the part of an unscrupulous consumer a similar series of 45 events will transpire and either the apparatus will be restored to its proper working condition as designed by the company or the fuse will be blown and notice given of the defective adjustment of the circuits. As shown 50 in the drawings, the meter M' is in operation and meter M² cut out. The controlling-circuits and apparatus are in a position to permit instantaneous transfer of activity to meter M² by an operation of the switch 14. Suppose the switch to be thrown to contact 13, thereby opening the contact at 13^a. A circuit is thereby closed from the positive main by way of contact 13, contact 10, across the switch-blade to contact 10^a, and thence by the 55 electromagnet on the right hand to the neutral main. The energization of this electromagnet throws over the armature, opening the circuit at contacts 10 and 10^a and closing it at 11 and 11^a. Simultaneously the establish- 60 ment of a ground at G provides a circuit through the switch-blade 9 and contact 13 to the positive main and from the ground G at

the consumer's station through the electromagnet 5^a to the neutral main, thereby simultaneously actuating the rate-changing switch 70 and shifting it from contacts 7 7^a to contacts 8 8^a, by which the shunt-circuit of meter M' is opened and that of meter M² closed, thereby transferring the period of activity to meter M². If now in any position in which the 75 switch 14 is set an accidental ground should occur on either side of the system or on either of the mains not grounded by the instrument, the closed ground connection of one electromagnet of the rate-maintainer from the neutral wire would render the magnet active and shift the rate-maintainer to the other control-wire. Simultaneously the ground at G in the consumer's station connected through one electromagnet with the neutral wire would 80 operate said electromagnet and shift the rate-changer. In the new condition of the controlling-circuits thus produced, however, the position of the switch 14 on its contact—say 85 13^a—would restore the apparatus to its previous condition as soon as the ground ceased. If the latter were permanent in character, the fuse 12 would be blown, thereby calling the attention of the employee to the accident to the circuits. In Fig. 2 a similar organization 90 95 is shown, an advantage, however, being obtained in that the grounding, which may affect the controllers, can only be from one side of the system, thus greatly reducing the liability of the system to derangement. In this 100 figure the fixed terminals of the switch 14 connect with the outside mains. The grounding, therefore, of the neutral or of one of the outside mains will not affect the system; but a ground on the other main will operate in 105 the same manner as described in connection with Fig. 1. As the full potential across the outside mains is necessary to operate the magnets, obviously the ground on the positive side in the condition of the circuit illustrated 110 would change the adjustment of the apparatus, which, however, if the ground were temporary in character would be immediately corrected.

What I claim as new, and desire to secure 115 by Letters Patent of the United States, is—

1. A control system for a multirate-meter, comprising a ground-control circuit, and electromagnetic devices included therein at the consumer's station and at the control-station, 120 including an automatic circuit-changer to reset the apparatus in case of an accidental ground, and thereby maintain the rate for which the meter was set.

2. A control system for multirate-meters, 125 comprising an electrically-controlled switch at the consumer's station for changing the meter-rate, a ground-controlling circuit from a distant point of the system, and means for automatically restoring the switch if operated 130 by a temporary ground.

3. In a multirate-metering system, a switch at the consumer's station for changing the meter-rate and a ground-control circuit for

said switch including a supply-wire, and an electrically-operated rate-maintainer at the control-station for restoring said switch if shifted by an accidental ground.

5 4. In a multirate-metering system, a ground-control circuit for setting the meter-rate, two automatic switches controlled thereby at the consumer's and control station, respectively, maintaining the ground from different supply-wires, and a periodically-operated switch at the control-station for grounding the automatic switch from either supply-wire.

5 5. In a three-wire multirate-metering system, a ground-control circuit for changing the meter-rate, including two magnetically-controlled switches at the consumer's and control station, respectively, completing a ground for an outside and neutral wire, contacts governed by the switches for transferring the 20 relative connection with the control-wires, whereby the meter-switch is reset if changed by a temporary ground, and an indicator at

the control-station operated by a permanent ground.

6. A multirate-metering system comprising 25 a control-circuit connecting the consumer's station and a control-station, a magnetically-controlled meter-rate-changing switch at the former, a magnetically-controlled rate-maintaining switch at the latter, contacts with 30 the control-circuit governed by the several switches for rendering their movements conjoint on a change of the control-circuit and circuit connections for effecting a restoration of the maintaining-switch if disturbed by 35 independent operation of the rate-changing switch.

In witness whereof I have hereunto set my hand this 3d day of August, 1899.

EUSTACE OXLEY.
